CONVERGENCE COIL ASSEMBLY
 Vincent J. Patti, Norridge, Ill., assignor to Thompson Ramo Wooldridge, Inc., Cleveland, Ohio, a corporation of Ohio
 Filed Mar. 6, 1963, Ser. No. 263,304
 5 Claims. (Cl. 317—200)

The present invention relates to an improved electromagnetic convergence assembly for a cathode ray tube.

The convergence assembly of the present invention is designed for operation with a color kinescope of the type employing a luminescent screen as part of a target electrode structure. Such screens include different phosphor areas which produce differently colored light when excited by electron beam components striking the target structure from different angles, the angle of impingement determining the particular color of the light produced by the phosphor areas.

For the satisfactory operation of such kinescopes, it is necessary to effect substantial convergence of the different electron beams at all points of the raster scanned by the beams at the target electrode structure.

One commonly used type of apparatus for controlling the convergence of a plurality of electron beams at a target electrode structure includes individual electromagnetic means located symmetrically about the axis of the tube neck and adjacent to the predeflection paths of the respective beams, and energized from the beam deflection circuit in a manner sufficient to effect the desired beam convergence. Typically, the individual convergence electromagnets are energized by waves which are available from both the vertical and horizontal deflection circuits which provide the scanning deflection of the beams.

Since the electron guns which produce the various electron beams in a color kinescope are symmetrically arranged about the periphery of the tube neck, it is important that the magnetic circuits must be similarly aligned. The difficulty arises because the neck diameters of various color kinescopes vary within substantial limits, on the order of one-quarter inch between extremes. There is a distinct mechanical problem presented, therefore, in employing a particular convergence electromagnetic assembly with tubes of various sizes, since it is necessary that the magnetic circuits retain their proper orientation with respect to the longitudinal axis of the kinescope while still retaining the symmetrical orientation of the magnetic structures about the tube neck.

In view of these requirements, the mechanical structure for housing the convergence electromagnets may become quite complex and hence expensive. Furthermore, such structures frequently require considerable assembly time, particularly in the matter of securing external leads to the coils.

One of the objects of the present invention is to provide an improved convergence coil assembly which is usable with kinescopes having different neck diameters.

Still another object of the invention is to provide a convergence coil assembly for color kinescopes which is economical to manufacture and assemble.

A further object of the invention is to provide an improved type of housing for convergence coil assemblies making it considerably simpler to connect external leads to the coils contained within the housing.

A further object of the invention is to provide an improved type of housing for convergence coil assemblies, which housing has permeability adjusting means accessible from the outside of the housing to vary the reluctance of the magnetic circuits contained in the housing.

A further description of the present invention will be made in conjunction with the attached sheets of drawings which illustrate several embodiments of the invention.

In the drawings:

FIGURE 1 is a view in elevation of an improved convergence coil assembly according to the present invention, illustrating the manner in which the assembly is placed about the neck of a cathode ray tube, a portion of the assembly being shown in completely assembled relation, another being shown with a portion of the housing removed to show the interior construction and a third portion of the assembly being shown completely devoid of magnetic components to illustrate the configuration of the housing section;

FIGURE 2 is a plan view of the assembly shown in FIGURE 1 looking upwardly into the structure;

FIGURE 3 is a view similar to FIGURE 1 but illustrating a somewhat modified form of the invention; and

FIGURE 4 is a fragmentary view of the tube engaging portion of the housing, on an enlarged scale, and also illustrating the coupling means by which the separate housings of the convergence coil assembly are interlocked.

As shown in the drawings:

In FIGURE 1, reference numeral 10 indicates generally an assembled convergence coil assembly consisting of three identical housings 11, 12, and 13 disposed symmetrically about the longitudinal axis of the neck of a kinescope whose neck has been diagrammatically illustrated by means of the dashed lines 14.

Each of the housings 11, 12, and 13 is conveniently made from molded resinous materials such as polyethylene, polystyrene, or the like. Each of the housings is made in two sections 16 and 17 which mate along a line 18. The configuration of the section 17 is best illustrated in FIGURE 1 of the drawings, particularly in the lower left hand and lower right hand portions. As shown in that figure, the section 17 includes opposed wall portions 19 and 21 and a base portion 22 which provides a seat for receiving a U-shaped magnetic core 23. A spring member 24 is bottomed on the wall 22 and urges the core 23 inwardly so that its pole faces 26 and 27 are snugly received in correspondingly shaped recesses 28 and 29 provided in the section 17.

The legs of the core member 23 are provided with a plurality of coils on each leg, consisting of a vertical frequency exciter coil 31 and a horizontal frequency exciter coil 32 mounted on one leg, and a corresponding vertical frequency exciter coil 33 and a horizontal frequency exciter coil 34 and mounted on the opposed leg. The corresponding vertical frequency exciter coils 31 and 33 and the horizontal frequency exciter coils 32 and 34 may be connected together. External connections from the coils are made by means of conductors 36, 37, 38, and 39 which are connected to conductors 41, 42, 43, and 44 respectively. These last named conductors are part of a cable illustrated generally at reference numeral 46.

One of the features of the present invention resides in the configuration of the housings by which external connections to the cable 46 may be made rapidly, conveniently, and inexpensively. For this purpose, the interior structure of the housings are provided with posts 47 and 48 disposed in the corners and a centrally disposed post

60 49 in the area of a slot 51 formed in the section 17 to accommodate the cable 46. Additional posts 52 and 53 are disposed intermediate the ends of the housing. The posts 47, 48, 49, 52, and 53 all extend the full thickness dimension of the two mating sections 16 and 17, that is, they are received snugly within suitable apertures formed in the section 16 and serve to lock the two sections together. Additional posts 54 and 56 of lesser height than the aforementioned posts are also provided to serve as wire guiding means within the housing as will be explained more fully in the succeeding description.

For convenience in assembly, the conductors constituting the cable 46 can all be cut to the same length and then

the bared ends can be tinned by dipping them in molten solder. Then, the conductors are slipped through the slot 51, and their lengths are adjusted by the manner in which they are led past the various posts and wall structure within the section 17. For example, the conductor 42 which must have the longest effective length to be connected with the conductor 37 of the coil 32 is passed directly around the core seat, and then between the post 52 and the inner wall of the housing 17. The clearance provided in this space is sufficiently small so that the conductor 42 is pinched and held against displacement by the close fit. Conductor 41 is to be secured to the lead 36 of coil 31 is provided with a more tortuous path to shorten the effective length. The conductor 41 first is trained about the centrally disposed post 49, then around the corner post 47 and about a baffle 56 extending from the inner wall of the section 17 and terminating short of the core seat. Then, the conductor is pinched between the post 54 and the inner wall of the section 17.

Similarly, the conductor 44 passes directly from the slot 51 between a baffle 58 and the wall 21 which forms a part of the seat structure for the magnetic core. The conductor then passes directly between the post 53 and the inner wall of the section 17 where is it pinched and held in proper alignment so that it may be connected to the conductor 39 extending from the coil 34.

The effective length of the conductor 43 is shortened by first training it about the centrally disposed post 49 then about the corner post 48, between the baffle 58 and the wall 21, and then between the post 55 and the inner wall of the housing 17. The conductor 43 is then at a level at which it can be conveniently connected to the lead 38 extending from the coil 33.

The housings 11, 12, and 13 are held together in interlocking relationship about the neck 14 at the kinescope. For this purpose, each of the housings is provided at one end with bifurcated portion 61 which is arranged to receive a foot portion 62 of an adjoining housing in sliding relation. The bifurcated portion 61 also carries an abutment 63 which tends to hold the foot portion 62 within the bifurcated portion 61 upon relative pivotal movement between the two. A C-shaped spring 64 acting between the foot portion 62 and the bifurcated portion 61 tends to keep the housings in interlocked relationship.

Each of the housings is provided with means accessible from the outside to vary the reluctance of the magnetic circuit existing between the magnetic coil structure contained in each of the housings and internal pole pieces (not shown) within the tube neck 14. The specific adjusting means shown in FIGURE 2 consist of a sleeve 66 which is held in position by means of a bracket 67 secured to the back of the section 17. The sleeve 66 receives a ferromagnetic member 68 in sliding relation therein and the position of the ferromagnetic member 68 thereby provides a means for controlling the magnetic characteristics of the coil assembly after it has been mounted onto the tube neck.

Another feature of the present invention resides in the configuration of the tube engaging surfaces of the housings 11, 12, and 13 to accommodate necks of different diameter. This construction is best illustrated in FIGURE 4 of the drawings. As evident from that figure, the tube engaging portions of the housing are composed of compound radii including a centrally disposed section having a minimum radius R_1 , and the two adjoining portions extending outwardly from the central portion, each having a maximum radius R_2 . The radius R_1 is chosen to correspond to the smallest radius tube which the convergence coil assembly will accommodate, and the maximum radius R_2 is chosen to represent the longest radius. Tubes having radii intermediate the extremes will be engaged by the housing where the sections of different radii merge as illustrated in reference numeral 71 in the drawings. Thus, regardless of the size of the tube neck, the housings will always engage the tube neck firmly while maintaining the

5
10
15

proper alignment between the magnetic core and the longitudinal axis of the tube neck.

The structure shown in FIGURE 3 differs in certain particulars from the structure of FIGURES 1 and 2. Where the elements are common between the two structures, however, the same reference numerals have been applied. The difference occurs in the type of magnetic core which is employed. In the form of the invention shown in FIGURE 3, the magnetic core consists of two L-shaped pieces 72 and 73 upon which the coils 31, 32, 33, and 34 are mounted. The seat provided for the core structure is also different in that it includes a window 74 for the purpose of providing access to an adjusting disc 76 composed of ferrite or other high permeability material, the disc 76 being urged against the abutting sides of the core legs 72 and 73 by an undulating spring 77 which also serves to urge the magnetic core pole pieces 26 and 27 tightly against the recesses 28 and 29 in the housing. Rotation of the disc 76 is thereby effective to vary the reluctance of the magnetic circuit.

The manner of interlocking the housings 11, 12 and 13 is also modified from the form shown in FIGURES 1 and 2. In this embodiment, the housings are interlocked by providing a set of coil springs 78 extending between angularly disposed lugs 79 on the exterior of the housings.

From the foregoing, it will be understood that the convergence tube assemblies of the present invention are economical to manufacture and considerably simplify the problems of wiring. Furthermore, they are readily adaptable for use with kinescope tubes having varying neck sizes without distorting the proper alignment which should exist between the coil assemblies and the longitudinal axis of the kinescope.

It should further be evident that various modifications can be made to the described embodiments without departing from the scope of the present invention.

I claim as my invention:

1. An electromagnetic convergence assembly for a cathode ray tube comprising:
a plurality of individual housings disposed symmetrically about a central axis,
spring means connecting said housings together,
each of said housings having means for receiving a coil structure therein and posts therein in close proximity to the inner walls of said housings, a coil seated in each of said housings, electrical leads extending into said housings and connected to the coils, at least some of said posts being spaced from said walls with a sufficiently small clearance so that said electrical leads passing therebetween are pinched between said posts and said inner walls.

2. An electromagnetic convergence assembly for a cathode ray tube comprising:
a plurality of individual housings disposed symmetrically about a central axis,
spring means connecting said housings together,
each of said housings having means for receiving a coil structure therein, and posts therein in close proximity to the inner walls of said housings, a coil seated in each of said housings, electrical leads extending into said housings and connected to the coils, at least some of said posts being spaced from said walls with a sufficiently small clearance so that said electrical leads passing therebetween are pinched between said posts and said inner walls, and permeability adjusting means accessible from outside said housings for adjusting the reluctance of the coil assemblies confined within said housings.

3. In an electromagnetic convergence assembly, a coil structure comprising:
a housing,
means in said housing defining a seat for a coil core,
a core disposed in said seat,
a plurality of coils disposed on said core,
said housing having an arcuate surface on the periphery

thereof arranged to engage the neck of a cathode ray tube,
 said surface having differing radii therealong,
 the shortest radius existing centrally of said surface,
 and the larger radii existing outwardly from the center 5
 of said surface.

4. In an electromagnetic convergence assembly, a coil structure comprising:
 a housing,
 means in said housing defining a seat for a coil core, 10
 a core disposed in said seat,
 a plurality of coils disposed on said core,
 posts within said housing spaced about the coil seat
 and in close proximity to the inner walls of said
 housing, 15
 there being a sufficiently small clearance between some
 of said posts and said inner walls so that an elec-
 trical conductor is pinched therebetween, said hous-
 ing having an arcuate tube engaging surface on the
 periphery thereof,
 said surface having differing radii therealong,
 the shortest radius existing centrally of said surface
 and the larger radii existing outwardly from the
 center of said surface. 20

5. In an electromagnetic convergence assembly, a coil structure comprising:
 a housing,
 means in said housing defining a seat for a coil core,
 a core disposed in said seat,
 a plurality of coils disposed on said core, and a ferro-
 magnetic disc in abutting relation to said core,
 said housing having a window therethrough permitting
 rotation of said disc from outside said housing,
 said housing having an arcuate tube engaging surface
 on the periphery thereof,
 said surface having differing radii therealong,
 the shortest radius existing centrally of said surface
 and the larger radii existing outwardly from the
 center of said surface.
